J. A. HAINES

CONNECTER FOR GARMENT BANDS

Filed Feb. 25, 1927

FIG. 1.

FIG. 2.

FIG. 3.

FIG. 4.

FIG. 5.

UNITED STATES PATENT OFFICE.

JOSEPH A. HAINES, OF PHILADELPHIA, PENNSYLVANIA, ASSIGNOR, BY MESNE ASSIGNMENTS, TO FRIEDBERGER-AARON MANUFACTURING COMPANY, OF PHILADELPHIA, PENNSYLVANIA, A CORPORATION OF PENNSYLVANIA.

CONNECTER FOR GARMENT BANDS.

Application filed February 25, 1927. Serial No. 170,788.

The object of my invention is to provide a new and useful adjustable connecter for the ends of flexible bands, and more particularly knee and waist bands intended and adapted for insertion into the circumferentially extending pocket formed around the leg or waist portion of a bloomer or other article of wearing apparel. This annular pocket may be, and usually is, formed by 10 folding the circular marginal part of the fabric down upon itself and stitching the edge of this marginal part to the body. An elastic band may be inserted under the folded section before stitching, or it may be inserted, after stitching, through an orifice in the folded section. The length of the band when not under tension is substantially less than the normal length of the circumferential pocket in the garment, so that, 15 after insertion of the elastic band, the material of the annular part of the garment enclosing the band contracts to form a series of folds or puckers extending transversely of the circumference. This part of the garment is therefore readily expansible circumferentially, which operation occurs in putting on the garment. After the garment is donned and after the elongating pull has been released, the elastic band shortens to 20 the extent required to embrace the waist or leg, as the case may be, of the wearer.

It is desirable to provide means whereby the elastic band may be conveniently inserted into the annular pocket and the ends 35 then united. The introduction of the band has been effected heretofore by means of a bodkin and the opposite ends of the band have been provided with mutually engageable clasps, which are secured together after 40 the band has been inserted.

My invention contemplates the use of a single "connecter" which may be attached to one end of the band and be engageable with the other end of the band, or which is entirely 45 separate from the band and is engageable with both ends of the band, the latter construction being preferable. One of the principal features of the invention, however, is the provision of a connecter so constructed 50 that one end or both ends (preferably both ends) of the band is, or are, adjustable relatively to the connecter, so that, either before or after the band is applied to the garment, the circumferential length of the band

may be adjusted to give the precise tension 55 with which it is desired that the band shall embrace the waist or leg.

Preferred embodiments of the invention are shown in the accompanying drawings, in which—

Fig. 1 is a plan view of one form of connecter.

Fig. 2 is a plan view of another form of connecter.

Fig. 3 is a perspective view of the connecter of Fig. 1 engaged with the ends of 65 a band.

Fig. 4 is a perspective view of the connecter of Fig. 2 engaged with the ends of 70 a band.

Fig. 5 is a front view of a part of a garment provided with an annular pocket and a perspective view of part of a band with the connecter of Fig. 1 secured to one end thereof, preparatory to inserting the band 75 into the pocket.

Fig. 6 is a plan view of still another form of connecter.

The preferred construction shown in Figs. 1, 3 and 5, comprises a connecter in the form 80 of a plate *a*, which may be flat, but preferably is curved, in the direction of its length, on a rather long radius, and which is provided with two pairs of orifices. Each pair of orifices comprises a transverse slot *b* (or 85 *b'*) and a longitudinally extending slot *c* (or *c'*). The two slots *b* and *b'* are located relatively near opposite ends of the plate. The two slots *c* and *c'* are more distant from the respective ends and are relatively close 90 to each other. Each slot *c* or *c'* tapers in width toward its companion slot *b* or *b'*.

One end of the elastic band *d* is engageable with the connecter *a* by passing such end successively through slot *b* and slot *c*, 95 the band wedging itself into the narrow end of slot *c* and being thereby more securely held from slipping. The other end of the band is similarly engageable with slots *b'* and *c'*.

Either or both ends of the band are adjustable relatively to the connecter so that the band may be given, when not under tension, any exact circumferential length desired.

It is preferred to elongate one end *a'* of the plate *a* and shape it like the front end of a bodkin, so that it may perform the func-

tion of a bodkin in the insertion of the band through the hole x of the annular pocket y of a garment z , as shown in Fig. 5.

In Figs. 2 and 4, the connector e is provided with a bodkin end e' , but is provided with only one pair of band-holding orifices b and c . Near its other end, plate e is provided, on opposite edges, with laterally extending ears f , f , which are bent down over one end of the band, as shown in Fig. 4, so as to confine that end of the band securely between the body of the plate and the ears. This mode of securing the connector to one end of the band does not permit of ready adjustment of that end of the band with relation to the connector, but such adjustment is not required, inasmuch as all the needed adjustment may be secured at the other end of the band.

In Fig. 6, the connector g is provided with two laterally extending orifices b^2 , b^2 , located near opposite ends of the connector and a single intermediate longitudinally extending orifice c^2 having opposite ends wedge-shaped. The construction is the same as that of Fig. 1 except that a single orifice c^2 is substituted for the two orifices c and c' .

The three embodiments of my invention shown and described herein are illustrative merely, and other modifications may be made without departing from the invention, the essential features of which are recited in the claims.

Having now fully described my invention, what I claim and desire to protect by Letters Patent is:

1. A connector for securing together the ends of an elastic band, the same comprising a metal plate provided near opposite ends with laterally extending orifices through which opposite ends of the band are adapted to be passed, the metal of the plate being cut away between said lateral orifices to allow opposite ends of the band to be passed through the plate and to afford edges tapering toward each lateral orifice and adapted to bind the band between them and secure it against accidental disengagement from the holder.

2. A connector for securing together the ends of an elastic band, the same comprising a plate provided with an orifice of substantially greater length than width and whose lengthwise extension is lateral of the plate and another orifice of substantially greater length than width and whose lengthwise extension is longitudinal of the plate, one end of the band being adapted to be successively passed through said orifices, the longitudi-

nally extending orifice tapering in width 60 toward the end thereof nearest the lateral orifice to form a single band-securing crotch.

3. A connector for securing together the ends of an elastic band, the same comprising a plate provided with a laterally extending 65 orifice and a longitudinally extending orifice, through which orifices one end of the band is adapted to be successively passed, the end of the plate beyond the laterally extending orifice gradually contracting in width 70 toward its end to enable it to perform the function of a bodkin.

4. A connector for securing together the ends of an elastic band, the same comprising a plate provided with an orifice of substantially 75 greater length than width and whose lengthwise extension is lateral of the plate and another orifice of substantially greater length than width and whose lengthwise extension is longitudinal of the plate, one end of the band being adapted to be successively passed through said orifices, the longitudinally extending orifice tapering in width toward the end thereof nearest the lateral orifice to form a single band-securing crotch, 80 the end of the plate beyond the laterally extending orifice tapering in width toward its end to enable it to perform the function of a bodkin, and means to secure the other end of the band to the plate.

5. A connector for securing together the ends of an elastic band, the same comprising a plate provided with an orifice of substantially 85 greater length than width and whose lengthwise extension is lateral of the plate and another orifice of substantially greater length than width and whose lengthwise extension is longitudinal of the plate, one end of the band being adapted to be successively passed through said orifices, the longitudinally extending orifice tapering in width toward the end thereof nearest the lateral orifice to form a single band-securing crotch, 90 the end of the plate beyond the laterally extending orifice tapering in width toward its end to enable it to perform the function of a bodkin, and means to secure the other end of the band to the plate, said means comprising another pair of orifices similar in shape and arrangement to those provided for 95 engagement with the first named end of the band.

In testimony of which invention, I have hereunto set my hand, at Philadelphia, Pennsylvania, on this 21st day of February, 115 1927.

JOSEPH A. HAINES.
